Thomas J. Muller et al.
Letters Patent.

The Patents referred to in these Letters Patent and making part of the same containing a description in the words of the said Thomas J. Muller himself of his apparatus for moulding bushes or logs for chimneys, &c.

The apparatus for moulding bushes or logs for chimneys, &c., consists of a flask, such as is generally used by masons, of any convenient size, and face boards, or, boards of metal, fitting the size of the flask. The first board has the flange part of the pattern attached to it with bolts through the centre of the pins, and board of sufficient size to admit the barrel part of the pattern, and with holes for rivet holes, through the flanges, one near each corner, and through the board, the latter for the pins, fastened to the centre of the board extending to each flange part of the bushes or logs. There are four steady pins to this board two on opposite ends to agree with holes in the flask. The second board or plate has as many pins attached to it as there are rivet holes in the flanges on the first board and of sufficient length to pass through the first board into the flanges the depth of the counter-sink, leaving a space between the first and second boards equal to the thickness of the flanges on the first board, which space is formed by four steady pins, two on opposite ends attached to the second board passing through the first board and resting on the flask. There are also holes in this board to agree with holes in the first board at the centre of the pins. The third board or plate has the barrel part of the pattern attached to it, as many in number as there are flanges on the first board, of sufficient length to pass through the second and first boards, and that the centre of the flanges do not form the exact high and size of the bushes or logs on the first board. The fourth board has as many pins attached to it, as there are barrels attached to the third

board of a size to agree with the inside of the barrels and of sufficient length to extend into the barrels passing through the third and second and first boards, leaving a space between the fourth and third boards equal to the length of the barrels below the flanges on the first board, which space is covered by iron pins, two on opposite ends, attached to the fourth board passing through the third and second boards and resting on the first board. The fifth board placed in it to form the counter-sink to the rivet holes on the flanges. The process for moulding the bush is as follows. is by placing that part of the flask, commonly called the novel, in a convenient place for moulding, with the holes for the steady pins uppermost, then the first board (to which is attached the flange part of the flask) is placed on the flask the steady pins in the board fitting the holes in the flask to keep it from moving. Then the second board is placed on the first board, the third on the second, and the fourth on the third, two narrow strips of wood are put between the fourth and third boards (of sufficient thickness to fill the space) to prevent any variation by the pressure of the sand while moulding; then by turning the boards and flask over the exact shape and size of the bush or rays are to be seen on the first board, the sand is then thrown firmly into the flask (on the platform) until the flask is full, a board is then placed on the flask and the whole is turned bottom up, the two strips of wood between the fourth and third boards are taken out, and the fourth or top board (to which is attached the pins that extend into the barrel part of the flask) is kept firmly to its place to prevent the sand moulded in the barrels from rising when the third board, to which is attached the barrel part of platform, is drawn up to the fourth or top board, then the two boards (fourth and third) are taken off, then the second board (to which is attached the pins that fit the rivet holes in the flanges) is kept firmly to its place to prevent the sand that form the rivet holes in the flanges from rising when the first board, to which is attached the flange part of the platform, is drawn up to it. The second and first boards are then taken off.

and this part of the mould is finished; the other part of the flask, (commonly called the cope,) is moulded on the fifth board which has the plans in it to form the counter-sinks to agree with the iron holes in the flanges, a spur is moulded in the centre of this part of the flask to agree with the gates on the other part, this part of the flask is then placed on the other part of the flask, and the mould is then ready to admit the melted metal. Another board or plate may be added to the five already mentioned with holes in it, the size of the flanges for the flange plates to draw through to prevent the sand from breaking. When the cornets and patterns are placed ready for the sand to be thrown in, steel wires may be placed in the barrels instead of sand which makes the casting very hard and smooth. This principle of moulding applies to carriage boxes, bell, rings and most other small articles.
